STABILIZED CONTROL CIRCUIT

George W. Nagel, Pittsburgh, Pa., assignor to
Westinghouse Electric Corporation, East Pitts-
burgh, Pa., a corporation of Pennsylvania

Application March 18, 1950, Serial No. 150,443

6 Claims. (Cl. 175—335)

1

My invention relates to an electron discharge circuit and especially to a circuit for stabilizing an electron valve.

Conventional relay circuits frequently include a relay actuating coil connected in series with a grid-controlled gas-discharge type of electron valve. Since conduction through this type of tube cannot be interrupted by manipulation of the potential of its control grid, it is conventional to use an alternating voltage source for the anode-cathode potential. This effectively interrupts the current flow every cycle and thus restores effectiveness to the control grid.

This procedure necessarily means that the supply of energy to the relay circuit is intermittent. To avoid relay chattering, it is conventional to shunt a capacitor across the relay coil. The capacitor stores energy during the conductive portion of each cycle and discharges through the relay coil during the remainder of the cycle to cause the coil to remain actuated during the full cycle of the alternating current. A control voltage is impressed on the grid of the valve to cause it to become conductive. This control voltage gradually becomes more positive with respect to the cathode of the valve until a point is reached at which the control voltage causes the valve to become conductive. Current then flows through the relay coil.

In the usual arrangement, this control voltage increases gradually until, during some one positive half-cycle of the source voltage, the voltage impressed on the grid of the valve is just sufficient to cause the valve to become conductive when peak value of the source potential is impressed from cathode to anode on the valve.

I have found that in such a control circuit the valve becomes conductive, actuating the relay for one cycle, but the valve does not become conductive during the next succeeding half cycles. This causes the relay to close momentarily and open, remaining open for a few cycles. This operation is referred to as chattering of the relay. Relay chattering is a highly objectionable phenomenon.

In some circuit arrangements the control circuit is capable of impressing only a limited voltage on the control grid of the thyratron. Such a control circuit may be capable of starting conduction in the thyratron when the full voltage of the source is impressed across the thyratron but may be incapable of starting the thyratron when a slightly lower voltage is impressed on it.

A similar problem arises in the use of a cold-cathode gaseous-discharge valve. Conduction in

2

such a valve is initiated by a glow discharge between the control electrode and the cathode. The magnitude of the current required in this discharge to cause the initiation of anode-cathode conduction in the valve is dependent upon the voltage impressed on the anode of the valve. A circuit may be inoperative if the current available from the control circuit is limited to a value below that required to initiate discharge in the valve.

An example of a circuit which may at times be subject to such a difficulty is shown in the application of Schultz and Nagel, No. 12,038, filed February 28, 1948, entitled "Garage Door Opener" and which has become abandoned. The circuit shown in Fig. 3 of this application includes a cold-cathode gaseous-discharge valve 29 which is started by current flow from the photoelectric cell 4. The relay 28, connected to the valve 29, is shown symbolically as a winding. Such windings generally have a shunting capacitor to maintain the relay actuated during the negative half-cycle. The photo cell 4 must provide a current greater than a certain predetermined minimum if the valve 29 is to become conductive. After the first period of conduction, the relay circuit connected to the anode of the valve 29 impresses a back voltage on the valve and then a greater current flow is required between the grid 46 and the cathode of valve 29 to initiate conduction during the next positive half-cycle. Under some circumstances, the light which impinges on the photo cell 4 and the characteristics of the photo cell 4 may be such that the current from photo cell 4 is sufficient to initiate conduction in valve 29 for one cycle but is insufficient to initiate conduction during succeeding positive half-cycles. Thus the current required to fire the valve 29 is dependent upon its past history of conduction, i. e. a current which will cause conduction in a cycle after a non-conductive cycle may be insufficient to fire the valve during a cycle which follows a conductive cycle.

Accordingly, it is an object of my invention to provide a circuit for a gaseous discharge valve which allows the discharge valve to be equally responsive to a control regardless of its past history of conduction.

It is an object of my invention to provide a relay control circuit which will operate in response to a gradually changing control voltage but will not cause chattering of the relay.

It is a further object of my invention to provide a stabilizing system which maintains sub-

stantially infinite the transconductance of a grid-controlled electron discharge device.

It is a further object of my invention to provide a circuit for a grid-controlled electron discharge device which will maintain constant its circuit response to a control voltage.

My invention arises from the realization that this chattering of the relay is due to a decrease in the voltage impressed across the valve after a first conductive period due to the presence of a residual subtractive potential across a capacitor in its anode circuit. This effect varies the control potential and/or current required to initiate conduction of the valve during succeeding cycles and therefore changes its response to the control voltage.

The critical voltage which will cause the valve to become conductive is dependent upon the characteristics of the valve and upon the anode to cathode voltage impressed on the valve. The valve becomes conducting passing current through the relay coil and the capacitor associated with the coil. During the following negative half-cycle of the source voltage the capacitor partially discharges through the relay coil. During the next positive half-cycle, the capacitor is not completely discharged and it effectively reduces the anode to cathode voltage impressed on the valve below the peak value of the source potential. If the control voltage has increased only slightly or not at all since the previous half-cycle, it is not now great enough to cause the valve to become conductive when a voltage less than the peak value of the source voltage is impressed on the valve. Thus, in normal operations of conventional relay circuits, the control circuit may cause the valve to become conductive during part of one positive half-cycle of the source potential but be unable to cause the valve to become conductive in the next one or more positive half-cycles. The relay may, therefore, be released after having been actuated and a chattering of the relay may occur as it closes and opens repeatedly.

In accordance with my invention I provide a circuit in which the voltage impressed on the relay coil is derived from a resistor connected in series with a control thyatron. A rectifier connected in series with the relay coil prevents the voltage across the relay coil from affecting the operation of the control thyatron prior to conduction.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawing, the figure of which is a schematic diagram showing a preferred embodiment of my invention.

As shown in the drawing, a thyatron 3 is connected in series with a resistor 5 across a source 7 of alternating current. The coil 9 of a relay 11 is connected from one side of the alternating current source 7 through a rectifier 13 to the anode 27 of the thyatron 3. A capacitor 15 is connected across the relay coil 9. Terminals 17 are provided to impress a control voltage between the grid 19 of the thyatron and one terminal of the power source 7. A source 21 of biasing voltage may be connected from the cathode 23 of the thyatron 3 through a grid resistor 25 to the grid 19 of the thyatron 3.

In operation, the thyatron 3 is initially non-conductive. The control voltage impressed on the grid 19 of the thyatron becomes gradually more positive to a point at which it is just sufficient to cause the thyatron 3 to become conductive. The thyatron 3 conducts during the remaining portion of the positive half-cycle. A positive half-cycle is defined as the time during which the source voltage causes the anode 27 of the thyatron 3 to be positive with respect to its cathode 23. When the thyatron 3 becomes conductive, current flows from one terminal of the source 7 both through resistor 5 and through the relay coil 9 and the rectifier 13 to the anode 27 of the thyatron 3 and thence to the other terminal of the source 7. The capacitor 15 is charged during this time. During the negative half-cycle no current is flowing through the thyatron 3 and the capacitor partially discharges through the relay coil. Current flowing from the capacitor causes the relay 11 to remain closed during the negative one-half cycle.

During the next positive half-cycle, and before the thyatron 3 becomes conductive, the voltage impressed on its anode is substantially the voltage of the upper terminal of the power source 7. The residual potential across the relay shunting capacitor 15 does not reduce the impressed voltage on the anode 27 of the thyatron 3. Thus, during the second positive half-cycle the voltage impressed across the thyatron 3 is the same as it was during the previous positive half-cycle and the control voltage is again effective during the positive half-cycle to cause the thyatron 3 to become conductive. During each positive half-cycle, therefore, the voltage impressed across the thyatron 3 is the same as on all other positive half-cycles and the effect of the control voltage on the conductivity of the thyatron remains constant. If the control voltage is sufficient to cause the thyatron 3 to become conductive during one positive half-cycle, the same control voltage will be effective to cause the thyatron 3 to become conductive during each succeeding positive half-cycle and no chattering of the relay will occur.

I have found that a circuit according to the single figure having components of the following magnitudes operates satisfactorily:

Capacitor 15, 10 μ fd.
Relay 11, coil resistance 1100 ohms operates on 10 ma.
Resistor 5, 10,000 ohms
Thyatron 3, RCA type 1-C-21
Source 7, 115 v.
Rectifier 13, selenium rectifier with rating 130 v. A. C. current 50 ma.

No bias voltage 21 was used. I have found that the resistor 5 must have a resistance small with respect to the back resistance of the rectifier 13 but the resistance must be large enough not to overload thyatron 3.

Although I have shown and described a certain specific embodiment of my invention, I am fully aware that many modifications thereof are possible using the principles herein disclosed. My invention, therefore, is not intended to be restricted to the specific embodiment shown and described.

I claim as my invention:

1. In combination, an electric valve having an anode and a cathode, a resistor, circuit means connecting said resistor to the anode of said electric valve, terminals for impressing across said resistor and said electric valve in series a volt-

age, an inductor and a capacitor connected in parallel, a rectifier connected in series with said capacitor and inductor, circuit connections between said resistor and said rectifier, capacitor and inductors such that the direction in which said rectifier allows current flow is in the direction from anode to cathode of said electric valve.

2. In combination, an electric valve having an anode and a cathode, an impedance, circuit means connecting said impedance to the anode of said electric valve, terminals for impressing across said impedance and said electric valve in series a voltage, an inductor and a capacitor connected in parallel, a rectifier connected in series with said capacitor and inductor, circuit connections between said impedance and said rectifier, capacitor and inductors such that the direction in which said rectifier allows current flow is in the direction from anode to cathode of said electric valve.

3. In combination, an electric valve having an anode and a cathode, a resistor, circuit means connecting said resistor to the anode of said electric valve, terminals for impressing across said resistor and said electric valve in series a voltage, an inductor and a capacitor connected in parallel, an element having a resistance to current flow in one direction substantially different from its resistance to current flow in the other direction connected in series with said capacitor and inductor, circuit connections between said resistor and said element, capacitor and inductors such that the direction in which said element presents the least resistance to current flow is in the direction from anode to cathode of said electric valve.

4. In combination, a coil across which is connected a capacitor, an electric valve having an anode, a cathode and a control electrode, a rectifier, series connections between said coil, rectifier and electric valve, said rectifier being oriented to conduct current in a direction from said anode to said cathode of said electric valve, an impedance connected across said rectifier and

said coil, terminals for impressing pulsating voltage across said resistor and electric valve, and terminal means for impressing a control voltage on said control electrode.

5. In combination, a gaseous discharge device having an anode and a cathode, a resistor connected to said anode, connections for applying alternating current potential across said discharge device and resistor in series, an inductive load device, a capacitor shunting said load device, a rectifier, and means connecting said rectifier in series with said load device across said resistor, said rectifier being poled to conduct in the direction from the anode to cathode of said discharge device.

10 6. In combination, a gaseous discharge device having an anode and a cathode, an impedance connected in series with said discharge device, connections for applying alternating current potential across said impedance and said discharge device; an inductive load device, a capacitor shunting said load device, a uni-directional conducting device connected in series with said inductive load device across said impedance, said uni-directional conducting device being poled to conduct in the direction of anode to cathode of said discharge device.
